INVENTOR

John Lackner
BY Chas. C. Gill
ATTORNEY

UNITED STATES PATENT OFFICE.

JOHN LACKNER, OF LONG ISLAND CITY, NEW YORK.

SOUVENIR-CARD.

No. 895,771.

Specification of Letters Patent.

Patented Aug. 11, 1908.

Application filed May 4, 1908. Serial No. 430,687.

To all whom it may concern:

Be it known that I, JOHN LACKNER, a citizen of the United States, and a resident of Long Island City, in the county of Queens and State of New York, have invented certain new and useful Improvements in Souvenir-Cards, of which the following is a specification.

The invention relates to improvements in souvenir-cards; and it consists in the novel features and structure hereinafter described, and particularly pointed out in the claims.

The object of my invention is to provide a souvenir-card comprising two backs which may be locked together, for purposes of transmission, and upon the opening or unfolding thereof disclose an attractive picture of a gradually appearing and disappearing character, whereby an illusionary effect may be produced, the picture preferably comprising a figure which is concealed when the card is closed and which will gradually appear through an opening in a portion thereof as the card is opened and likewise disappear through said opening during the closing of the card.

The card of my invention comprises four features, namely, the two outer backs or covers connected together in a hinged manner at adjoining end edges, a bridge-piece connecting said cards at about the middle portions of their facing sides and capable of folding and unfolding, so as to permit said outer covers to be opened from and closed toward each other, and a figure secured to the covers adjacent to their hinge and projecting through a slot in said bridge-piece, whereby as the covers are opened said figure will become gradually exposed by the lowering of said bridge-piece downwardly over the same, and during the closing of said covers said figure will be gradually concealed by the upward folding movement of the middle portion of said bridge-piece over the same.

The invention will be fully understood from the detailed description hereinafter presented, reference being had to the accompanying drawings, in which:

Figure 1 is a face view of a souvenir-card constructed in accordance with my invention, the backs or covers of the card being shown in their interlocked position; Fig. 2 is a view of the reverse side of the card, the enclosed figure being denoted by dotted lines; Fig. 3 is an enlarged longitudinal section of the same on the dotted line 3-3 of Fig. 2;

Fig. 4 is an edge view of the card, shown in its open position, the central figure being partly broken away, and Fig. 5 is a view showing the card tilted or partly in perspective and taken from one end of Fig. 4.

In the drawings, 10, 11 designate the cover-sections of the card, 12 the central figure or picture-strip inclosed between the same, and 14 the bridge-piece which connects said cover-sections 10, 11 at their inner faces and above their lower hinged ends and which bridge-piece, due to its capability of folding, permits said cover-sections to be opened and closed, said cover-sections being preferably in one integral piece folded on the line 9 to constitute a hinge at the inner adjacent ends of said sections. The outer surface of one cover-section may be used for an address, as denoted in Fig. 1, and the outer face of the other cover-section may be left plain or suitably illustrated or bear inscriptions, as may be desired.

The figure 12 is shown as being in the outline of a woman pictured as dressed in bathing costume, and said figure will preferably be formed from a piece of reasonably stiff paper or card-board cut out to the outline of the figure pictured thereon and having at its lower or inner end-edge a flap 15 which is pasted to one of the cover or back sections adjacent to the hinge of the latter, so that the figure may stand vertically between said sections. The flap 15 is turned upwardly so that the figure may stand in the same plane with the hinge-line of the cover or back-sections 10, 11, as shown in Fig. 4.

The bridge-piece 14 is preferably formed of a strip of paper creased outwardly along its transverse middle line, as at 16, and therein formed with a narrow slot 17, through which the outer portion of the figure 12 slightly projects when the card as a whole is closed, and through which also the figure 12 gradually appears and disappears as the cover-sections are opened and closed.

The bridge-piece 14 is formed at its ends with the inwardly turned flaps 18 which are pasted to the facing sides of the cover-sections 10, 11 outwardly from the hinged ends of the latter and preferably at about the middle or slightly below the middle of said sections, and by preference the bridge-piece 14 will be of the same width as said cover-sections and bear a scene appropriate to the character delineated by the figure 12. For illustration, the figure 12 shown is that of a

woman in bathing costume, and hence the scene on the bridge-piece is represented as the waves of the ocean from which the figure will seemingly appear as the card is opened 5 and into which it will disappear as the card is closed. A representation of Neptune would also be appropriate for the figure 12 when a water scene is depicted on the bridge-piece 14. While the same is not essential in every 10 instance, I preferably extend the scene over the entire outer surface of the bridge-piece 14 and cause both sides of the figure 12 to present the same picture, so that the interior of the card may be viewed, while the latter is 15 being opened or closed from over the outer end of either cover-section.

The inner surfaces of the cover-sections 10, 11, outwardly from the ends of the bridge-piece 14, may be utilized to receive 20 writing or other inscriptions, as the owner of the card may elect.

It is preferable that the cover-sections 10, 11 be normally locked together at their free or outer ends, especially during transmission 25 through the mail, and to this end I provide one section adjacent to its outer end with a slot 19 to receive a tongue 20 formed on the end of the other cover-section, as shown. The cover-sections being of flexible material, 30 such as stiff paper or card-board, no difficulty will be experienced in inserting the tongue 20 through the slot 19 without breaking or materially bending the sections; and said tongue when inserted through the slot 35 19 will bind the outer ends of the cover-sections together.

I do not limit the invention to any special picture to be delineated on the figure-strip 12 nor to any special scene to be presented on 40 the outer surface of the bridge-piece 14, but recommend that said picture and scene be appropriate to each other so that the card may present an artistic effect and its value be enhanced accordingly.

45 Figs. 1, 2 and 3 show the card in its closed position. When the cover-sections are unlocked by the withdrawal of the tongue 20 from the slot 19 and gradually opened from each other, the bridge-piece 14 is extended 50 and caused to gradually slide down on and to an increasing extent expose the figure-strip 12, the latter appearing to ascend from the slot 17 in the creased line 16 of said bridge-piece, and when the cover-sections 55 10, 11 are gradually closed toward each other, the middle portion of the bridge-piece 14 gradually folds upwardly on and to an increasing extent conceals said figure-strip 12,

the latter seemingly descending through the slot 17 or disappearing. The slot 17 is made 60 very narrow so that the figure strip may seem to appear from and disappear into the scene pictured on the bridge-piece 14.

The card may be used as a souvenir postal card or as a novelty, and the figure-strip 12 65 will vary in accordance with what it may be desired to represent thereby.

What I claim as my invention and desire to secure by Letters Patent, is:

1. A card comprising cover-sections hinged 70 together at adjoining edges, a foldable bridge-piece connecting said sections at their inner faces outwardly from the hinge, and a strip bearing a figure secured to a cover-section adjacent to said hinge and extending through 75 said bridge-piece; substantially as set forth.

2. A card comprising cover-sections hinged together at adjoining edges, a foldable bridge-piece connecting said sections at their inner faces outwardly from the hinge, and a strip 80 defining at its edges an outline figure and bearing a picture fitting said outline, said strip being secured to a cover-section adjacent to said hinge and extending through said bridge-piece; substantially as set forth. 85

3. A card comprising cover-sections hinged together at adjoining edges, a foldable bridge-piece connecting said sections at their inner faces outwardly from the hinge, and a strip bearing a figure secured to a cover-section 90 adjacent to said hinge and extending through said bridge-piece, one of said cover-sections having a slot adjacent to its free end and the other cover-section having at its free end a tongue to be inserted through said slot and 95 lock said sections in closed position; substantially as set forth.

4. A card comprising cover-sections hinged together at adjoining edges, a foldable bridge-piece outwardly creased and slotted at its 100 middle portion and at its ends having flaps fastened to the inner faces of said sections, and a strip bearing a figure and having at its inner end a flap secured to a cover section at 105 said hinge, said strip thence extending between the folded portions of said bridge-piece and through the slot therein; substantially as set forth.

Signed at New York city, in the county of New York, and State of New York, this 1st 110 day of May A. D. 1908.

JOHN LACKNER.
